(57) **CLAIM**

The ornamental design for a plunger drip tray, as shown and described.

DESCRIPTION

FIG. 1 is a top perspective view of a plunger drip tray;

FIG. 2 is a bottom perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a rear elevation view thereof;

FIG. 8 is a front elevation view thereof; and,

FIG. 9 is a cross sectional view taken along lines 9-9 of the plunger drip tray in FIG. 3.

Those portions shown with cross-hatching lines in the sectioned side elevation view of FIG. 9 are to exemplify the sectioned profile and are for illustration purposes only, forming no part of the claimed design.
